UNITED STATES PATENT OFFICE.

HAZEN MOOERS, OF MILWAUKEE, WISCONSIN.

STEAM-RADIATOR.

SPECIFICATION forming part of Letters Patent No. 319,601, dated June 9, 1885.

Application filed July 28, 1884. (No model.)

To all whom it may concern:

Be it known that I, HAZEN MOOERS, a citizen of the United States, residing at Milwaukee, in the county of Milwaukee and State of Wisconsin, have invented certain new and useful Improvements in Steam-Radiators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in steam and hot-water radiators, and pertains, first, to the manner of connecting the upper ends of the series of radiating-sections together; second, to the manner of increasing the heat-radiation of the flues or section; third, to the devices for permitting the escape of air from the several sections as the steam or water enters them, all of which is herein explained by reference to the accompanying drawings.

Figure 1 represents a front view. Fig. 2 is a top view. Fig. 4 is an enlarged top view. Fig. 5 is a top view of two sections, showing the binding-rods by which the several sections are held in place and the shoulders upon one of the end sections which support the binding-rods. Fig. 6 represents the inner side of the upper end of one of the end sections, also the upper end of one of the radiating-plates. Fig. 7 represents a perspective of one of the separating-studs by which the upper ends of the sections are prevented from coming in contact. Fig. 8 represents a perspective view of one of the keys which are interposed between the separating-studs, and by which the upper ends of the several sections of the radiator are retained at the proper distance apart and in line with each other.

Like parts are represented by the same reference-letters throughout the several views.

A A are a series of radiating-sections, which are constructed at their lower ends in the ordinary manner. The opposite surfaces of the several sections A are provided with numerous conical-shaped projections, B, which serve to increase their radiating-surface. Between these projections are interposed a series of ver-

tically-arranged sheet-metal plates, C C, each of which are made of a single sheet of metal, preferably folded at its center, so as to bring the two halves of the sheet nearly parallel to each other, as shown in Fig. 2.

Between the folded leaves of the vertical plates C are inserted separating-rods M M, which serve to keep the leaves at the proper distances apart and in contact with the projecting ends of the radiating-points B, whereby said plates are kept at a high temperature and the heat-radiating capacity of the radiator is increased. I preferably arrange the folded edge of the plates C toward the front with the edges of the leaves rearward, as, when thus arranged, they present a neater appearance.

The lower ends of the series of sections A A are coupled together by the series of screw-cut coupling-sleeves D D in the ordinary manner, while their upper ends are connected together by the horizontally-arranged rods E E.

When screwing the coupling-sleeves D together, it is difficult to bring all the sections to the same relative position to each other, owing to the variation of length of the thread on said sleeves, and as a consequence the space between the upper ends of the sections also vary slightly, corresponding to the spaces between their lower ends, to prevent the sections from being broken apart at their sleeves or from being inclined or drawn out of parallel one with another by the binding-rods E E as the retaining-nuts G are turned, and to retain the sections in line with each other I provide the opposing surfaces of the several sections with separating-studs H, having notches S for the reception of the tapered keys or wedges T. When the lower ends of the several sections are secured together with the sections in line with each other, the ends of each pair of opposing studs are brought nearly or quite in contact with each other in such a manner that the two notches of such studs together form a rectangular space for the reception of the key T. The key T, when inserted, serves the two-fold purpose of retaining the upper ends of the sections in line with each other, and for adjusting the relative distances between the upper ends of the sections to conform to the dis-

tances between their lower ends. Thus, when the lower ends of the sections are farther apart than the upper ends would be with the studs in contact, the wedge or key T is driven into 5 the key-space until the sections are brought parallel to each other. When the lower ends are too near, the key T is partially withdrawn from the key-space, and in this manner the several sections are all brought into line 10 parallel with each other when the nuts on the binding-rods E are tightened, whereby the sections with the keys are all held rigidly in place.

I am aware that the sections of a radiator 15 have been rigidly locked together with horizontally-arranged dovetail keys without the aid of rods, as shown in Patent No. 105,640. I therefore make no claim to such device.

Having thus described my invention, what I 20 claim as new, and desire to secure by Letters Patent, is—

1. In a hot-water or steam radiator, the combination, with the series of sections A A, of the series of sheet-metal plates C C, interposed 25 between the opposing surfaces of said sections, substantially as set forth.

2. In a hot-water or steam radiator, the combination, with the series of sections A A, of the series of sheet-metal plates C C, interposed between the opposing surfaces of said sections, 30 and series of separating-rods M M, substantially as and for the purpose specified.

3. The combination of the several sections A A, provided with notched studs H, tapered keys T, interposed between the contiguous 35 ends of the respective studs, and retaining or binding rods E, supported at their respective ends in bearings upon the end sections, substantially as set forth.

4. The combination, with the two end sections A A, of the shoulders F F, binding-rods E E, provided at one or both ends with nuts G G, notched studs H, and tapered keys T, all substantially as and for the purpose specified.

In testimony whereof I affix my signature in 45 presence of two witnesses.

HAZEN MOOERS.
